UNITED STATES PATENT OFFICE.

BERTIE E. MILLS, OF CHICAGO, ILLINOIS, ASSIGNOR TO MILLS NOVELTY COMPANY, OF CHICAGO, ILLINOIS, A CORPORATION OF ILLINOIS.

MUSIC-SHEET FEEDER.

Application filed August 3, 1921. Serial No. 489,470.

To all whom it may concern:

Be it known that I, BERTIE E. MILLS, a citizen of the United States, residing at 231 South Green Street, Chicago, in the 5 county of Cook and State of Illinois, have invented a new and useful Improvement in Music-Sheet Feeders, of which the following is a specification.

My invention relates to an improvement 10 in the music-sheet feeder of U. S. Letters Patent No. 1,302,439 dated April 29, 1919 to H. K. Sandell; and it relates particularly to an improvement in the means for automatically reversing the driving motor to 15 rewind the music-sheet from the feed-roll upon the music-roll.

The primary object of my improvement is to simplify the mechanism by dispensing 20 with the solenoids (denoted 306 and 307 in Fig. 40 of said patent) and the plurality of contacts of the motor-controlling switch which is operated by the solenoids.

In the accompanying drawings, Figure 1 is a view in front elevation of the music- 25 sheet feeder embodying my improvement; Figure 2 is a partly broken view of the same in end elevation, and Figure 3 is a section on line 3—3, of Fig. 1, diagrammatically illustrated.

With the exception of my improved means, 30 the mechanism may be that shown and described in the Letters Patent to which reference is made; so that only so much of said mechanism illustrated in the present drawings need be described herein as is required 35 for understanding the construction and operation in connection therewith of my improvement.

To facilitate identifying parts with the 40 aforesaid patent, the reference-numerals in the latter are employed in the following description on corresponding parts to be described in connection with the present drawings.

The armature-shaft of the electric motor 45 70 carrying the fly-wheel 73, is provided with the studs 74 for engaging the T-head 75 of the worm-shaft 76 meshing with the housed worm-wheel 83 to drive the feed- 50 roll 55 for taking up from the music-roll 123 the music-sheet 213. The sheet crosses the contact-roll 148 in frictional driving contact therewith and against which the contact-brushes, one of which is represented at 203 55 in Fig. 3, bear when they register with per-

forations in the music-sheet. On the outer end of the music-roll drive-shaft 105 carrying the pinion 104, to which rotation is imparted by the gear 86 for rewinding the sheet through the idler 100, is the clutch-device 60 involving the brake-shoe carrying arms 115.

The stub-shaft 150 (Fig. 1), extending from an end of the contact-roll 148 and having a bearing in the governor-frame 165, carries the bevel gear 168 meshing with the 65 bevel pinion 169 on the governor-shaft 170 carrying the wobble-governor 175 and the sliding collar 176 linked to the governor and serving to make contact with the brush 179 extending from the pendulum 180. 70

The bar 239 which extends from the arm 214 of the spring-retracted brush-carrying pivotal frame (denoted 195 in the aforesaid patent) engages, by the turning of the frame to drop the brushes 203 away from the contact-roller 148, the insulated spring-contact 240, all as explained in said patent, to reverse the motor for rewinding the sheet from the take-up roll onto the music-roll. 75

The roller 248 provided on one end of the 80 spring-retracted bell-crank 246 to bear against the music-sheet on the take-up roll 55, carries on its opposite end the spring-controlled contact-finger 251 to engage, as and for the purpose hereinafter explained, 85 the adjacent edge of the contact-plate 255 (Fig. 3) of insulated material on the frame of the machine; and a spring-pressed contact-arm 5 pivoted to the support, which has a stop 6 to limit the movement of the 90 arm under the tension of the spring 8, is provided to be engaged by a spring contact-finger 7 on the adjacent bell-crank arm.

The primary purpose of my improvement 95 is the same as that of the rewinding mechanism in the said patent, that is to say, when the predetermined length or entire perforated portion of the sheet has been stripped from the music-roll, the driving motor is caused to automatically reverse, the brush-frame will be tilted backwardly to withdraw the brushes from contact with the music-sheet; the re-wind gear will be set in motion, the motor-speed accelerated and the music-sheet re-wound upon the music-roll 100 at desired accelerated speed. When the perforated sheet has been thus re-wound, the motor will again automatically reverse, the re-wind gear will be released, the brush-carrying frame will approach the music-sheet and 105 110

bring the brushes into proper relation thereto, and the take-up roll driving-shaft will then be engaged and again driven in the playing direction. This I now accomplish 5 in the following-described manner, reference being had particularly to Fig. 3:

The line-wires *a* and *b* may be those of any suitable constant potential circuit. The line-wire *a* is, in practice, grounded to the 10 frame of the machine, the points of grounding being indicated at *x*, *y* and *z*, respectively. At 9 is indicated the winding for the field which produces rotation of the armature for driving the take-up roll in the direction for 15 winding the sheet upon it, and at 10 is indicated the reversing field. As the parts are represented in Fig. 3, the music-feeder is in operating condition to cause the sheet to be wound upon the take-up roll from the music- 20 roll, a switch-lever 12 then engaging a contact 11 to close the circuit over the wire *a* and frame (from *x* to *y*) through a resistance-coil 13 to the field 9 and thence over the return line-wire *b*. A portion of the current 25 passes from the resistance 13 over a branch *a'* of the circuit to the governor, which operates as described in the said patent and performs no function in the rewinding operation.

30 The accumulation of the music-sheet on the take-up roll, in pushing against the roller 248, gradually turns the bell-crank 246 on its insulated fulcrum to bring the finger 7 into contact with the arm 5, the contact-finger 35 251 meantime snapping past the plate 255. The duration of the brush-contact with the roll 148 is only momentary, being followed by the turning of the brush-frame to withdraw the brushes away from the contact- 40 roll, with the result of bringing the bar 239 against the contact 240, all as explained in the said patent, whereby the current goes to the reversing field 10 as well as to the field 9, reversing the motor and causing the sheet to 45 be speedily rewound from the take-up roll upon the music-roll.

As the take-up roll becomes depleted, the resultant turning of the bell-crank under the force of its retracting spring 253 separates 50 the finger 7 from the arm 5, which would break the circuit with impulses owing to the imperfectly cylindrical condition of the remainder of the sheet on the take-up roll, were it not that in the meantime the finger 55 251 has encountered and remained in rubbing contact with the plate 255 to maintain the circuit-closure when the members 5 and 7 separate, until the unwinding from the take-up roll terminates, whereupon the con-

tinued turning of the bell-crank will complete withdrawal of the finger 251 past the plate edge with the result of quickly opening the circuit and reversing the motor into the playing direction.

When, while the music-sheet is traveling 60 from the roll 123 to the roll 55, it is desired to reverse the motor for rewinding the sheet at any time before it has been completely wound upon the take-up roll, as for repeating one of a plurality of the musical compositions which the music-sheet is adapted to reproduce, this may be done by manipulating the switch-lever 12 to bridge the two contacts 11 and 11¹, thereby causing the current to go, as the showing in Fig. 3 makes clear, 75 to the reversing field 10 and field 9.

In the diagrammatic view, the switch 12 is shown in dotted representation to be turned against a stop 14. In that position 80 of the switch, the circuit is open and the motor is not running.

I claim:

1. An electric music-sheet feeder comprising the rotatory sheet-connected music and take-up rolls, an intermediate contact-roll 85 rotated by the sheet in travelling across it, a reversible electric motor, brush-mechanism cooperating with the contact-roll, a reversing gear for the music-roll and a spring-retracted bell-crank having a roller on one 90 end co-operating with the feed-roll, characterized by an electric circuit containing the contact-roll, the brushes and the bell-crank, a spring-pressed contact-arm included in said circuit with a contact-finger on the bell- 95 crank, normally separated from said arm and brought into contact therewith to reverse the motor for rewinding the sheet by turning of the bell-crank by the take-up roll, and manually operated switch-mechanism 100 for opening and closing the circuit.

2. The electric music-sheet feeder according to preceding claim 1, characterized by a spring-controlled pivotal contact-finger on the opposite end of the bell-crank and a contact-plate presenting an edge into the path of said finger, said plate and finger being included in the circuit. 105

3. The electric music-sheet feeder according to preceding claim 1, characterized by the switch-mechanism having one contact for the switch-lever controlling the motor-field for driving the take-up roll in the sheet-winding direction and a second contact controlling the reversing field of the motor 110 when the switch-lever is bridged across both contacts. 115

BERTIE E. MILLS.
